EXTENSION TABLE

Louis W. Wokosin, Oshkosh, Wis.

Application October 20, 1934, Serial No. 749,285

2 Claims. (Cl. 311—72)

This invention relates to extension tables and more particularly to an equalizer slide construction whereby companion sections or sides of the table top, can be simultaneously moved an equal 5 distance in opposite directions, thereby extending the table top to project an equal distance beyond the table legs, thus balancing the overhang.

The invention together with its objects and advantages will be best understood from a study 10 of the following description taken in connection with the accompanying drawings wherein:

Figure 1 is a bottom view the extended position of the table top being indicated by dotted lines.

Figure 2 is a side elevational view and,

Figure 3 is a transverse sectional view through the table.

Referring more in detail to the drawings, 5—5 designates side and end strips of a table frame supported in the usual manner by legs 6. Mounted 20 on the frame of the table is a top formed of companion sections or sides 7 and 8 respectively.

In accordance with the present invention the table top sections 7 and 8 are provided on their under side with opposed cleats 9 having on their 25 inner faces longitudinal grooves 10 which accommodate guide pins 11 projecting laterally and outwardly from the side strips 5 of the table frame, whereby provision is made for holding the table top sections 7 and 8 slidable on the frame 30 against undue movement in a vertical plane.

Further in accordance with the present invention the side strips 5 in their upper edges are provided with longitudinal grooves 12 in which operate pins 13 depending from the under faces 35 of the top sections 7 and 8, and which pins work in the grooves 12 in a manner to hold the table top sections 7 and 8 against undue lateral movement.

To effect an equal adjustment of the table top 40 sections 7 and 8, there is provided an equalizing bar or slide structure 14 that is pivoted intermediate its end as at 15 to a transverse brace bar 16 that extends between the side strips 5 of the table frame, and which is secured at its end to 45 said side strips 5 by glued tennoned joints, or in any other suitable manner. On the top face thereof the bar 14 is provided with spaced parallel longitudinal grooves 17 in which operate groove followers or pins 18 provided on the under 50 side of the table top sections 7 and 8 adjacent

the inner meeting edges of said sections. To permit easy rotative movement of the bar 14, and to provide proper clearance between the ends of the bar and the side members 5 of the frame said bar 14 has its ends rounded off in reverse direction as at 14a.

From the above described construction it will be obvious, that by reason of the bar 14 and the pin and groove connections between said bar and the table top sections 7 and 8, it will be obvious 10 that when either of the table sections 7 and 8 is pulled outwardly the other table top section will be caused to move outwardly in the opposite direction an equal distance to that of the manually moved section, and then an additional table leaf 15 (not shown) may be inserted between the separated companion sections 7 and 8 to provide an enlarged table top. A slide structure embodying the features of the present invention will be found practical and efficient in operation, economical, 20 and possessive of a life of long duration.

Having thus described the invention, what is claimed as new is:

1. An extension table comprising a frame, companion table top sections thereon, interengaging 25 means on each of said top sections and the frame for retaining the respective sections in sliding engagement with the frame and against movement in vertical and lateral directions, and an equalizer structure connecting said sections for transmitting movement of one section to the other whereby said sections will be caused to move an equal distance in opposite directions, said equalizer consisting of an equalizing bar pivotally mounted within the table frame, and provided 30 with a pair of parallel grooves, and depending pins on the companion sections engaging in said grooves.

2. An extension table comprising a frame, companion table top sections mounted on the frame 40 for adjustment thereon, a brace bar extending between opposed members of the frame, an equalizer bar pivoted intermediate its ends on said brace bar and provided in its upper face with spaced parallel grooves, and depending pins on 45 the table top sections at the meeting ends of the latter and engaging in the grooves in a manner to cause the companion top sections to move an equal distance in opposite directions when effecting an adjustment of the table top.

LOUIS W. WOKOSIN.
